CLASP

Frank Headon, New York, N. Y.

Application November 18, 1944, Serial No. 564,030

9 Claims. (Cl. 24—245)

1

The present invention relates to clasps or fasteners adapted for holding material including fabric and the like and more particularly for clamping and holding wearing apparel such as thin hose or stockings. This application is a continuation in part of my copending application Serial No. 500,899, filed September 2, 1943, (now Patent No. 2,363,322, November 21, 1944).

An important object of the invention is to provide novel and advantageous devices which are effective for the general purposes indicated.

Another object of the invention is to provide a novel and simple form of clasp adapted to clamp thin fabrics without damage thereto.

Another object of the invention is to provide a novel and advantageous device of the general character indicated which is of very simple construction and is economical to manufacture.

Still another object of the invention is to provide a thin clasp in which there are two curved resilient members which may be clamped together by suitable longitudinal flexing thereof followed by a return from said flexed condition, and when clamped are held against relative transverse movement.

A further object of the invention is to provide a thin clasp comprising two thin curved plates having cooperating means at their ends rendered effective by flexing whereby the curved plates will not only be held against separation but will also be held against relative transverse movement edgewise thereof.

Yet another object of the invention is to provide a clasp comprising two thin longitudinally curved plates which may be clamped together at their ends by proper flexing and release, and may be held against relatively edgewise movement by a pivot at one side on which the two clasp plates are pivotally mounted.

A further object of the invention is to provide a clasp comprising two thin longitudinally curved plates which may be clamped together at their ends with the concave face of one plate cooperating with the convex face of the other plate and held against relative edgewise movement, by engagement of a part or parts on the edge of each plate with an edge of the other plate.

According to a preferred manner of carrying out the invention, use may be made of two thin longitudinally curved members or plates of resilient material, such as a suitable plastic material in its finished form. The inner plate has convex curved ends with their edges undercut with reference to the convex face and the outer plate has

a longitudinally concave inner face and at the ends of this concave face inwardly concave curved shoulders to engage the undercut curved ends of the inner plate. This arrangement serves not only to lock the plates together but also to prevent relative edgewise movement of the plates.

Such flexing of the plates is effected by straightening them so as to spread the shoulders apart and then when upon release the shoulders come toward each other they will engage the curved edges at the ends of the inner plate. The plates will then be locked together and the curved engaging surface at the ends will prevent relative edgewise movement. Both of the plates may be provided with central openings, thus rendering them more flexible and capable of relative adjustment and serving to render the device less conspicuous. Both plates may be provided with means for supporting the same. The clasped material is of course clasped between the plates and allowance must be made for the thickness of the fabric.

According to a second form the engaging ends and shoulders are straight and the plates may be held in proper longitudinal and transverse relations by means of a pivot passing through aligned openings in projections at the edges of the plates and in engagement with each other.

According to a second form the engaging ends and shoulders are straight and the plates are held against transverse edgewise movement by one or more projections at the edge of each member and engaging an edge of the other. Other objects, features and advantages will be apparent upon consideration of the following detailed description and of the drawings in which

Fig. 1 is a front elevation of a device embodying the present invention;

Fig. 2 is a sectional view taken along the line 2—2 of Fig. 1;

Fig. 3 is a section taken along the line 3—3 of Fig. 1;

Fig. 4 is a view on a larger scale of the structure at an end of Fig. 2 showing a piece of fabric held between the plates;

Fig. 5 is a front elevation of another or second clasp embodying the present invention;

Fig. 6 is a section taken along the line 6—6 of Fig. 5;

Fig. 7 is a section taken along the line 7—7 of Fig. 5;

Fig. 8 is a front elevation of another or third form of clasp embodying the present invention;

55 and

Fig. 9 is a section taken on the line 9—9 of Fig. 8.

Referring to the drawings, there is illustrated in Figs. 1, 2, 3 and 4 a clasp 10 embodying a preferred form of the invention. This clasp comprises a thin resilient rear plate 11 curved longitudinally to present a convex front surface and a front plate 12 also curved longitudinally to present a concave rear face to cooperate with the front face of the rear plate in clasping material such as fabric 13 (Fig. 4).

To hold the two plates together in clasping position, the front plate 12 is made longer than the rear plate 11 and is provided at its inner, or concave face near its ends with inwardly facing shoulders 14 to cooperate with outwardly facing shoulders 15 constituting the end surfaces of the rear plate 11. Due particularly to the longitudinal curvature of the rear plate 11 its ends or shoulders 15 may be considered as under-cut. By pressing plates 11 and 12 together and suitably flexing them the shoulder 14 may be brought to positions to produce a locking cooperation thereof through fabric 13.

To guard against relative transverse movement of plates 11 and 12, the shoulders 14 and 15 may be initially shaped transversely of the plates as by making the shoulders 14 of concave transverse curvature and the shoulders 15 of corresponding convex curvature. Preferably both plates 11 and 12 are of generally oval shape with symmetrical curved ends and with the central portions thereof in substantial coincidence and adapted to engage opposite faces of the fabric.

The plates 11 and 12 may also be provided with central openings 16 and 17 (Fig. 2) respectively which may be of oval shape and of substantially the same size. These openings serve to render the plates 11 and 12 more flexible thus enabling better adjustment therebetween in clamping the fabric. To support the clasp 10, plate 11 is provided at one side edge with a projection or lug 18 having a slot 19 therethrough, plate 12 is provided with a corresponding projection 20 with a slot 21, and a tape 22 is passed through both slots 19 and 21. Obviously separate tapes might be used in slots 19 and 21 but a single tape tends to maintain the parts in proper relative position.

In the modification illustrated in Figs. 5, 6 and 7, there is a curved rear plate 11a having straight ends 15a and a front plate 12a having at the ends of its inner face inwardly facing straight shoulders 14a to cooperate with said straight ends 15a. In this form relative transverse movement of plates 11a and 12a is prevented by means of the suspension means. To this end the rear plate 11a is provided at one side edge midway of its length with a single extension or lug 18a having at its outer end a bore 18c extending through the lug from edge to edge to receive a pivot pin 23 which also passes through bores 20c in lugs 20a extending from the corresponding side edges of plate 12a and with parts thereof engaging parts of lug 18a to hold the plates in proper relative position longitudinally thereof. The pivot pin 23 may be supported in any suitable manner as by a bail 24 connected to the ends of pivot pin 23, and a tape 22 passing therethrough.

In the form illustrated in Figs. 8 and 9, the plates 11b and 12b are provided respectively with straight ends 15b and straight shoulders 14b and the rear plate is provided with an opening 16b to render it more flexible. The principal difference between this form and that of Fig. 6 resides

in the manner of supporting the plates 11b and 12b. As illustrated the rear plate 11b has an upwardly extending central lug 18b which also projects forwardly over the upper edge of plate 12b and the front plate 12b has at opposite sides of lug 18b, upwardly extending lugs 20b which project rearwardly above the upper edge of plate 11b. Also the lug 18b has a slot 19b to receive a tape and the lugs 20b have slots 21b to receive tapes. As illustrated the central lug 18b on the rear plate 11b has a broad base and is tapered at both ends so that it decreases in width toward the top. Also the lugs 20b have broad bases so as to overlap the base of 18b at opposite sides, and the inner edges of lugs 20b are inclined so that the lugs decrease in width toward the top. Due to this arrangement the parts projecting from these lugs over the adjacent plates must be cut away to correspond. This arrangement tends to avoid too sharp bends in the fabric.

The operation of closing and opening the clasps is substantially the same in all forms. The closing may be effected by grasping the front and rear plates at both ends, flexing both plates to straighten them and releasing the flexing pressure while maintaining the ends in their engaged position. The unclasping action may be carried out by taking one end of the front plate and flexing this plate until it releases the rear plate. Or both ends of the front plate may be grasped at the same time to flex the same and release the clasp.

It should be understood that various changes may be made and that certain features may be used without others, without departing from the true scope and spirit of the invention.

Having thus described my invention, I claim:

1. A clasp comprising a resilient rear plate longitudinally curved to produce a convex front face and ends constituting undercut shoulders, a resilient front plate longitudinally curved to provide a concave rear face to cooperate with the convex front face of the rear plate in clamping fabric and the like and provided at the ends of its rear face with inwardly-facing shoulders for locking cooperation with said ends of the rear plate through thin material such as fabric, and means for supporting said clamp at one side thereof.

2. The combination according to claim 1 in which at the support edge of said clamp said inner and outer plates are hinged together.

3. The combination according to claim 1 in which a pivot pin passes longitudinally of the clasp through lugs projecting upwardly from the front and rear plates and having edge contact therebetween and a supporting device for said pivot pin is connected thereto.

4. The combination according to claim 1 in which alternately arranged lugs project from the upper sides of the front and rear plates and at their upper ends are slotted and extend laterally over the edges of the adjacent plates to prevent relative transverse movement.

5. The combination according to claim 1 in which alternately arranged lugs project from the upper edges of the front and rear plates and are broader at their bases and decrease in width toward their tops to said lugs, projecting over the upper edges of the other plates, engaging the sides of the other plates and decreasing in width upwardly to cooperate laterally with the lugs of upwardly decreasing width.

6. The combination according to claim 1 in which the ends of the rear plate are convex

transversely and said shoulders are concave transversely of the outer plate.

7. The combination according to claim 1 in which the ends of said rear plate are symmetrically curved and the edges of said shoulders are symmetrically curved to fit over the ends of the rear plate.

8. The combination according to claim 1 in which the rear and front plates are of oval shape and of the same width and the front plate is of greater length and the inwardly-facing shoulders at the ends of its rear face are curved to cooperate with the ends of said rear plate.

9. The combination according to claim 1 wherein the undercut shoulders of the rear plate and the cooperating inwardly-facing shoulders at the rear face of the outer plate are provided with means to prevent relative lateral movement between the plates.
